SCRUB PAIL

Clarence P. Neats, East Orange, N. J.

Application July 17, 1934, Serial No. 735,707

3 Claims. (Cl. 15—264)

This invention relates to scrub pails and has for an object to provide an improved construction wherein the pail may be readily shifted from place to place while in use without raising the same from the floor.

Another object of the invention is to provide a scrub pail wherein there is provided two compartments for water or other cleaning fluid, and separate compartments for soap, brushes and the like.

An additional object is to provide a scrub pail wherein the sides have flaring tops to prevent splashing of the cleaning fluid or soap suds.

In the accompanying drawing—

Figure 1 is a perspective view of a scrub pail disclosing an embodiment of the invention;

Figure 2 is a top plan view of the scrub pail shown in Fig. 1, the same being on an enlarged scale;

Figure 3 is a longitudinal vertical sectional view through Fig. 2, approximately on the line 3—3;

Figure 4 is a transverse sectional view through Fig. 2 approximately on the line 4—4;

Figure 5 is a detailed fragmentary sectional view through Fig. 2 on the line 5—5, a cake of soap being shown in position.

Referring to the accompanying drawing by numerals, 1 indicates the body of the pail which is provided with flaring top side members 2 and 3, and flaring end members 4 and 5. If desired a partition 6 could be arranged in the body 1, as shown in Fig. 3, so that two kinds of liquid may be contained in the pail if desired. The bottom of the pail is provided with a plurality of pressed out portions 7 acting as legs for supporting that end of the body so that it will be at the same height as the front end which is provided with rollers 8 and 9, said rollers being on a

shaft 10 supported by suitable brackets 11. When it is desired to pull or push the pail over the surface of a floor, the end 5 is grasped and preferably slightly raised and then pulled or pushed whereby the rollers 8 and 9 may function.

As the pressed out portions 7 are rounded the pail may be pulled or pushed along the floor without being raised. The tabs 12 and 13 are riveted or otherwise rigidly secured to the ends of the body 1, said tabs having apertures for receiving the looped ends 14 and 15 of the bail 16. This bail is adapted to be used to carry the pail from place to place when walking, but when kneeling or sitting on the floor, usually the end 5 is grasped and the pail pulled or pushed along as desired.

The top side members 2 and 3 are provided with a plurality of brackets 17 designed to act as stops or abutments for different articles, and also as supports for a bar or rail 18. As shown in Fig. 1, a brush 19 rests on the top side member 2 and against rail 18. The remaining place adjacent the brush 19 may be filled with another brush or a wiping cloth, if preferred, while the respective compartments 20 and 21 may be filled with water or other liquid.

A cake of soap 22 is adapted to be carried by the holder 23, which is riveted to the top side member 3 and is provided with overhanging side flanges 24 and 25 and a stop 26, said stop having an aperture 27 whereby any liquid may readily drain therefrom. As shown in Fig. 5 the flanges 24 and 25 are adapted to project into the soap 22 and hold it against movement when the brush 19 or other member is moved back and forth thereover. The inclination of the flanges 24 and 25 permits the ready use of different sized cakes of soap and acts to hold the same in place at all times, so that the maximum use of the soap may be obtained, and also so that the soap will be held in a convenient position for use at all times. When scrubbing floors or other surfaces, the brush 19 may be rubbed against the soap, applied to the surface to be scrubbed, and later rubbed again to the soap and again applied. In this way as much soap may be applied as desired, but none of the soap will be wasted.

During the rubbing of the brush back and forth over the cake of soap, some of the water or soap suds may flip therefrom. If this happens such matter will merely strike the end flaring members 4 and 5 and therefore, will not produce any undesirable results.

I claim:

1. A scrub pail including a rectangular body having at the top portion flaring sides and ends, said ends and sides acting as handles and as supports for various articles, means on one of said sides acting to receive and prevent a cake of soap from shifting, means on the opposite side presenting a plurality of brackets, and a connecting bar forming a rack for receiving different articles.

2. A scrub pail including a hollow body open at the top, traction means connected to said body exteriorly thereof near one end, said body having at the top flaring sides and ends, a bail swingably connected with said ends, a plurality of inclined flanged members on one of said flaring sides for receiving a cake of soap, and a plu-

rality of brackets and connecting means on the other flaring side for receiving separate articles.

3. A scrub pail including a hollow substantially rectangular body open at the top and having at the upper edge flaring end and side members, an apertured tab rigidly secured to each end of said body and projecting to a point sufficiently above the lower edge of said flaring end

members to position the apertures therein substantially midway of the height of said flaring end members, a bail with the ends extending through the apertures in said tabs, and means on the respective flaring side members for receiving and supporting articles. 5

CLARENCE P. NEATS.
